COLIN KYLE, OF SAN JOSE, CALIFORNIA, ASSIGNOR, BY MESNE ASSIGNMENTS, TO UNITED REPRODUCERS PATENTS CORPORATION, OF ST. CHARLES, ILLINOIS, A CORPORATION OF NEVADA

ACOUSTIC DEVICE

Application filed March 12, 1928. Serial No. 260,833.

This invention relates to a condenser, or electrostatic type of acoustic device, and especially to a modified form of the device shown in my former patent entitled "Acoustic device" Number 1,644,387 issued October 4, 1927.

The device shown in the patent referred to consists of a rigid perforated metallic plate, a thin flexible metallic plate and an intermediate flexible dielectric diaphragm. An electric potential applied to the plates causes electrostatic attraction which varies according to the degree of applied potential, and movement is therefore transmitted to the flexible metallic plate and the diaphragm, which produces sound or acoustic vibrations in the air coupled therewith.

I have discovered that the thickness of the dielectric diaphragm interposed between the rigid and the flexible plates, and the material employed in the diaphragm, plays an important factor in the successful operation of an acoustic device of the electrostatic type; that is, materials such as thin sheets of mica, celluloid, treated paper etc., presenting a hard, unyielding surface to the rigid perforated plate, and as such tend to produce a mechanical rattle or buzzing sound when the device is in operation. While diaphragms which are constructed of a soft or yielding material, such as thin sheets of rubber, rubberized silk, linen, or cotton fabrics etc., are free from mechanical sounds, the hard or unyielding materials such as paper, celluloid, mica etc., are, as a rule the best dielectrics and furthermore can be made much thinner. As such they are the most desirable, but the mechanical sound produced is so objectionable as to practically render such materials worthless.

I have now discovered that the mechanical sound produced can be entirely avoided if a soft or yielding buffer material is interposed between the dielectric diaphragm and the surface of the rigid plate. A thin layer of this material is the equivalent of a soft pad interposed between two hard surfaces, and as such prevents rattle and buzzing sounds.

The object of the present invention is ac-

cordingly that of generally improving and simplifying the construction and operation of acoustic devices of the character described, and particularly to interpose a soft buffer material between the diaphragm and the rigid plate, so that diaphragm materials presenting a hard unyielding surface may be employed.

The invention is shown by way of illustration in the accompanying drawings, in which:

Fig. 1 is a plan view of the acoustic device, said plan view being partially in section and partially broken away to show the different plates, the diaphragm and the buffer material,

Fig. 2 is a transverse cross section of the acoustic device,

Fig. 3 is an enlarged cross section of a portion of the acoustic device.

Referring to the drawings in detail, A indicates a rigid perforated metallic plate which is provided with an annular rim 2. The plate may be constructed of practically any material, that is steel, iron, brass, copper, aluminum, etc., but it should be sufficiently thick or heavy to prevent it from vibrating when the acoustic device is in operation. The plate may have any exterior contour desired but it is, in this instance, shown as circular or disk shaped in form. The surface presented is rounded or spherical, and it serves as a support for buffer material generally indicated at B, a flexible diaphragm C and a flexible metallic plate generally indicated at D. The buffer material is interposed between the rigid plate A and the diaphragm C, and a number of different buffer materials may be employed, such as a coating of thin rubber, granulated rubber, soft gelatin substances, and the like. Any material which has the quality of being comparatively soft and resilient may be employed, and it may be dielectric, partially dielectric, and in some instances may even be formed of material having electric conducting qualities.

The flexible metallic plate D may consist of practically any material, for instance any of the metals which are capable of being

rolled into a thin leaf, such as gold leaf, aluminum leaf, etc., or it may consist of any electric conducting material, whether metallic or otherwise, such as graphite, sprayed metal, metal deposited by electrolytic action, plated, or a material dipped in a solution such as chloride of gold etc.

In one form of the invention as actually constructed and used, an ordinary perforated 10 steel plate of 16-gauge metal is employed, as illustrated at A in the drawings. This plate is cut circular or otherwise, and is provided with a rim 2. The main face is hammered, or subjected to die action to produce a rounded 15 or spherical surface. A thin coating of rubber, as indicated at B, is then applied to one surface of the flexible diaphragm. This coating of rubber may be partially vulcanized and the surface treated with soapstone or the like, so as to produce a resilient soft yielding 20 non-adhesive surface. The diaphragm is then stretched over the surface of the rigid plate A and is secured in any suitable manner, or as here shown by a clamping ring or 25 band 3. The buffer material contacts with the upper surface of the plate A, and the diaphragm presenting a hard surface, may thus be employed, as mechanical rattle is prevented by the interposition of the buffer material.

After the diaphragm has been applied, a 30 flexible metallic plate may be formed, for instance by applying a thin coating of metal, by metallic spray, electrolytic deposition, plate, or by pasted gold leaf or the like, to 35 the exterior surface of the diaphragm. The device so constructed is ready for use, and may be connected with any radio set whether transmitting or receiving, in fact may be employed in any circuit where transmission or 40 reception of sound is required, as it will function both as a microphone and as a loud speaker. If connected with a radio receiving set, it has power amplification in the audio frequency side of the circuit. The two terminals leading from the audio frequency 45 amplifying circuit are connected, one to the flexible plate and one to the rigid plate. A modulated, or varying current potential is in this manner made with the surrounding 50 atmosphere and the potentials imposed on the plates will be transmitted into sound or acoustic vibrations.

I found that an ideal buffer between the diaphragm and the rigid plate may be formed 55 by applying a thin coating of rubber cemented to the inner face of the diaphragm and then sprinkling on a thin coating of granulated rubber, such as shown at 4 (see Fig. 3). This prevents contact of the hard 60 surfaces of the diaphragm and the rigid plate, and mechanical sound is completely eliminated. The buffer material accordingly permits use of diaphragm materials heretofore considered impractical, and it permits 65 use of thinner diaphragms. The importance

of a thin diaphragm is obvious, as the power or volume output of the speaker is in direct ratio to the square of the distance between the two plates.

While certain features of the present invention are more or less specifically described, I wish it understood that various changes may be resorted to within the scope of the appended claims; similarly, that the materials and finishes of the several parts employed 75 may be such as the manufacturer may decide or varying conditions or uses may demand.

I claim:

1. An acoustic device comprising a rigid and a flexible plate, a diaphragm interposed 80 between the plates, and a buffer material interposed between the diaphragm and the rigid plate.

2. An acoustic device comprising a rigid and a flexible plate, a flexible dielectric diaphragm interposed between the plates, and a buffer material interposed between the diaphragm and the rigid plate.

3. An acoustic device comprising a rigid and a flexible plate, a diaphragm interposed 90 between the plates, and a dielectric buffer material interposed between the diaphragm and the rigid plate.

4. An acoustic device comprising a rigid and a flexible plate, a diaphragm interposed 95 between the plates, and a buffer material secured to one face of the diaphragm and interposed between the diaphragm and the rigid plate.

5. An acoustic device comprising a rigid 100 perforated plate, a dielectric diaphragm covering the plate, a soft yielding material secured to one face of the diaphragm and interposed between the diaphragm and the rigid plate, and a flexible electric conductor 105 on the opposite face of the diaphragm.

COLIN KYLE.
